UNITED STATES PATENT OFFICE.

CHARLES G. BRAXMAR, OF NEW YORK, N. Y.

DESIGN FOR A BADGE.

SPECIFICATION forming part of Design No. 34,305, dated April 2, 1901.

Application filed February 21, 1901. Serial No. 48,375. Term of patent 7 years.

To all whom it may concern:

Be it known that I, CHARLES G. BRAXMAR, a citizen of the United States, residing in the borough of Manhattan, in the city and State 5 of New York, have invented and produced a new and original Design for a Badge, of which the following is a specification, reference being had to the accompanying drawing, forming part thereof.

As fully shown in the drawing, which is a face view, my badge has a general shield shape. It is slightly swelled or convex. Each side is formed with a gentle curve A A', terminating at the top in a quick curl A'. Cross- 10 ing the top, of even breadth with the depth of this curl, is a horizontal bar B. Above this is a symmetrical right-and-left scroll C. At the bottom is a blank space D, with an approximately trefoil form. Superposed on the 15 front is a figure of an eagle P, with its wings extended, its head turned toward its right, and its whole surface engraved to indicate plumage. This conspicuous feature lies mainly over the central area; but its wings extend out upon the border areas on each side. The 25 side curves A and the cross-bar B are of about equal width. Each has a border M on its inner edge and a border N on its outer edge. The border N is notched or scalloped. The central leaf of the bottom area D is of angular 30 outline.

Having described my invention, what I claim as new, and desire to secure by Letters Patent, is—

The design for a badge, as herein shown and 35 described.

In testimony whereof I have signed my name to this specification in the presence of two subscribing witnesses.

CHARLES G. BRAXMAR.
